[57] CLAIM

The ornamental design for a microwave oven, substantially as shown and described.

DESCRIPTION

FIG. 1 is a front, top and right side perspective view of a microwave oven showing our new design;

FIG. 2 is a front elevational view thereof;

FIG. 3 is a right side elevational view thereof;

FIG. 4 is a top plan view thereof;

FIG. 5 is a left side elevational view thereof;

FIG. 6 is a rear elevational view thereof; and

FIG. 7 is a front elevational view thereof, showing the transparent window within the dark colored door during operation.

FIG. 1

FIG. 2

FIG. 3

FIG. 4

FIG. 5

FIG. 6

FIG. 7
